UNITED STATES PATENT OFFICE.

JOHN DE MOOY, JR., OF CLEVELAND, OHIO, ASSIGNOR TO THE TAYLOR
& BOGGIS FOUNDRY COMPANY, OF SAME PLACE.

DESIGN FOR A LAMP-STOVE.

SPECIFICATION forming part of Design No. 18,624, dated September 25, 1888.

Application filed July 12, 1888. Serial No. 279,761. Term of patent 7 years.

To all whom it may concern:

Be it known that I, JOHN DE MOOY, Jr., a citizen of the United States, residing at Cleveland, in the county of Cuyahoga and State of Ohio, have invented and produced a new and original Design for Lamp-Stoves, of which the following is a specification, reference being had to the accompanying drawing, forming a part thereof.

10 Referring to the drawing, the figure is a perspective view of my improved design for lamp-stoves.

15 A is the reservoir, having the convex top B and provided with the front and rear curved, flaring, or convex projecting portions C, the four corners c of the reservoir being also curved or rounded. On the sides of the reservoir are the horizontal projecting handles, respectively, d d', the upper faces of which are in the 20 same general convex curve with the top of the reservoir, said handles being formed with curved outlines. The top grate, E, practically conforms in outline with the reservoir, with the exception of the side portions, e, which are 25 of right-line formation without the projecting handles of the reservoir; but said top grate is provided with the front and rear convex projecting portions F, and also with the rounded corners f.

30 The complete stove presents a graceful and

pleasing appearance to the eye, with its reservoir formed in curved outline and the top grate conforming in contour thereto.

I therefore particularly point out and distinctly claim as my invention—

35

1. In a design for a lamp-stove herein shown and described, a reservoir the periphery of one side portion of which is of flaring formation and having lateral indentations and rounded corners, substantially as set forth. 40

2. In a design for a lamp-stove herein shown and described, a top grate formed with a flaring side, lateral indentations, and rounded corners, substantially as set forth.

3. In a design for a lamp-stove herein shown 45 and described, the reservoir formed with a convex top, the vertical front and rear walls of the reservoir of curved formation and provided with rounded corners and a chimney or chimneys, and a top grate conforming in curved 50 outline with the reservoir walls, substantially as set forth.

In testimony that I claim the foregoing to be my invention I have hereunto set my hand this 9th day of July, A. D. 1888.

JOHN DE MOOY, JR.
